Hyman A. Rosen

Attorney.

UNITED STATES PATENT OFFICE

HYMAN A. ROSEN, OF BALTIMORE, MARYLAND

INDICATOR AND REMINDER

Application filed September 9, 1931. Serial No. 561,860.

My invention relates to improvements in indicators and reminders, providing a simple means of advising the tradesman of the needs of the moment. The main purpose of this invention is to obviate the necessity of writing a note or message by hand which may be blown away by the wind or rendered unintelligible by rain and further to act as a reminder when several items are desired.

While the drawings illustrate an embodiment of the invention with relation to its use on milk bottles as a message indicator for the milk man, it is understood that without departing from the spirit or scope of the invention, the device can, by very minor changes in detail and construction, be varied so that it could be readily adapted for use on the grocer's bread box, for the housewife's kitchen, for the shopper or for any occasion where a reminder may be necessary or desirable.

The invention consists in the construction and arrangement of the several parts which are shown in the accompanying drawings and in which:

Figure 1 is an elevational view of the device with its covered sides.

Figure 2 is a detail vertical sectional view.

Figure 3 is a top plan view.

Figure 4 is a fragmentary elevational view, partly broken away.

The device is constructed to form a cover for a milk bottle and to clamp the head or mouth thereof. The device may be constructed of any material but a light weight sheet metal or aluminum is preferable. The device comprises a bottle engaging holder, a disk, a spring, a stud and a plurality of tab elements rotatable therewith.

The sides of the device 1-1 comprise a hollow sheet of material adapted to overlap and securely clamp the mouth of a milk bottle. The disk 2, is fixed to a rotatable stud or key 3, which rests upon a strong spring 4, firmly attached to a base 5. The disk Fig-

ure 3, includes a plurality of tab elements 6-6 which are firmly fixed to the stud 3, and rotate with said stud. Upon these tab elements 6-6 are printed a variety of items to indicate the article and amount of goods or products handled by the tradesman.

Over the tab elements on the dial of the device is a narrow strip of non-transparent material or metal 7, cut out substantially as shown in the drawings and covering and concealing about a third of the surface of the tab elements. This strip of metal runs along the circumference of the dial but is cut out forming an opening at points 8-8 which are depressed for the purpose of receiving the tab elements upon its surface. Over the whole dial mounted into the frame of the device is a transparent sheet of celluloid.

The practical operation of the device is as follows. The stud 3 is depressed upon the spring 4 and rotated until the particular tab element upon which the required message is printed appears in the cut out 8-8. The pressure upon the stud is then released but rotated to bring the tab element upon the strip or ledge 7 and so exposed to view. When the following and undesired tab element appears in the cut out, the stud is then again depressed and rotated under the strip and is so again concealed. It is apparent that more than one tab element or message may thus be rotated upon the strip 7 and exposed. The drawing in Figure 3 shows three tab elements 6a exposed, thus indicating three separate items or messages to the tradesman.

Various changes may be made in the form and details of the indicator without departing from the spirit of the invention.

What is claimed and desired to be secured by Letters Patent is:

1. An indicator device of the class described, comprising a body portion, a disk rotatably mounted thereon and having a plurality of relatively movable indicia carry-

ing elements, and annular ledge means carried by the body portion adjacent the disk normally concealing the elements, and formed for cooperation with the disk for exposing selected indicia carrying elements above the ledge.

2. An indicator device of the class described, comprising a body having a fixed ledge portion, a member provided with a plurality of individual relatively movable indicia carrying elements, said member mounted on the body with certain elements normally concealed by the ledge, and means for moving the member relative to the ledge for bringing certain selected indicia carrying elements to exposed position on the ledge.

3. An indicator device of the class described comprising a body with a fixed ledge secured adjacent the upper edge thereof, said ledge having a cut-out portion, a spring-pressed stud rotatably mounted within the body, a plurality of relatively movable indicia carrying elements fixed to the stud, said elements normally concealed by the ledge and selectively operable by the stud for movement from beneath the ledge through its cut-out portion to exposed position on the ledge.

4. An indicator device comprising a cylindrical body having an annular inturned radially slotted ledge, a yielding support mounted within the body, a stud rotatably resting upon the support, and a radial series of relatively movable indicia carrying elements fixed to the stud to be rotated therewith, said elements normally concealed by the ledge and selectively operable by the stud for movement from beneath the ledge through its radial slot to exposed position on the ledge.
